UNITED STATES PATENT OFFICE.

WILLIAM WHARTON, JR., AND EDWARD SAMUEL, OF PHILADELPHIA,
PENNSYLVANIA, ASSIGNORS TO WILLIAM WHARTON, JR., AND COMPANY,
INCORPORATED, OF SAME PLACE.

DESIGN FOR A RAILWAY-RAIL.

SPECIFICATION forming part of Design No. 18,325, dated May 15, 1888.

Application filed April 20, 1888. Serial No. 271,338. Term of patent 14 years.

To all whom it may concern:

Be it known that we, WILLIAM WHARTON, Jr., and EDWARD SAMUEL, both citizens of the United States, and residents of Philadelphia, Pennsylvania, have invented a new and original Design for a Railroad-Rail, of which the following is a specification.

Our design for a railway-rail is fully shown in the accompanying drawing, which represents a transverse section of the rail.

The rail has a depending web, *a*, at the top of which, on one side, is a laterally-projecting head having a flat top, *b*, and a depending lug, *d*, at its outer edge. From the opposite side of the web *a* projects a neck, *f*, terminating in a web, *g*, the lower portion of which forms a depending lug, *h*, below the neck *f*, while its upper portion, *i*, projects upwardly above the neck *f*, and between the rail-head and the projecting upper portion of the web *g* is a deep groove, *m*.

We claim—

The design for a railway-rail having the outline illustrated, and consisting of the depending web *a*, having on one side the laterally-projecting head with flat top *b* and depending lug *d*, and on the opposite side the projecting neck *f*, terminating in a web, *g*, with depending lug *h* and upper projecting portion, *i*, between which portion *i* and the head of the rail is a deep groove, *m*, all substantially as described and shown.

In testimony whereof we have signed our names to this specification in the presence of two subscribing witnesses.

WILLIAM WHARTON, JR.
EDWD. SAMUEL.
